CLAIM

The ornamental design for a housing for a water vapor distillation apparatus, as shown.

DESCRIPTION

FIG. 1 is a front-top perspective view of a housing for a water vapor distillation apparatus showing the claimed design;
FIG. 2 is a back-top perspective view thereof;
FIG. 3 is a right side view thereof;
FIG. 4 is a front view thereof;
FIG. 5 is a left side view thereof;
FIG. 6 is a back view thereof;
FIG. 7 is a top view thereof; and,
FIG. 8 is a bottom view thereof.
